UNITED STATES PATENT OFFICE

PETER J. SHRUM, OF MONACA HEIGHTS, PENNSYLVANIA

WIRE ARTICLE

Application filed March 1, 1928. Serial No. 253,357.

This invention relates to the making of articles of any desired shape from wire.

An object of this invention is to provide a new and improved wire article that shall be flexible and practically adapted for use as wearing apparel such as a belt, suspenders, and the like.

Another object of this invention is to provide a novel method of weaving an article that shall render such article very pliable and flexible.

A further object of this invention is to provide a wire article having the above characteristics and which can be readily and cheaply made.

These and other objects that may be made apparent throughout the further description of the invention are attained by means of the wire article and the method of making the same hereinafter described and illustrated in the accompanying drawings, wherein,

Fig. 1 is a partial plan view of the two ends of a wire belt; Fig. 2 is a fragmental view showing the method of weaving a wire belt; Fig. 3 is an enlarged partial plan view of a section of single layer loops; Fig. 4 is a similar view of one form of two-layer loops and Fig. 5 is a similar view of another form of two-layer loops; and Fig. 6 is a fragmental enlarged view, similar to Fig. 2, but showing a lesser number of loops per row and taken from the opposite side of the woven article.

Referring to the drawings, I show the two ends of a belt formed of one continuous piece of wire woven with a horizontal double stitch, each stitch comprising a row of loops such as shown at 11 having upper and lower curved portions 12 and 13. The loops 11 are bent so as to lap the curved portion 13 upon the corresponding curved portion 12 to form an upper and lower row of double loops, as shown at 12, 13 and 11, 11.

In carrying out the weave, any number of the loops 11 are bent to lap the curved portions 13 upon the corresponding curved portions 12 to form an article of any desired width, then the loop 11 next following is turned about its curved portion 13 and the following curved portions 13 are threaded

through the double loops formed by the co-operating curved portions 12 and 13 in succession. This operation is repeated until the article reaches the desired length at which time a number of wire loops 11 may be straightened for tying the last formed loops 12 and 13 to a belt buckle or the like, as shown at 14. The beginning of the wire article, that is, the first lower loops 11, 11 may be gathered up by a short wire or a portion of the same wire forming the loops and anchored in any suitable manner, such as shown at 15.

More specifically, the weave is formed from a continuous succession of loops (see Fig. 3) comprising upper curved portions 12_a etc., and lower curved portions 13_a etc. The weave is begun by bending the upper curved portion 12_a at points 11_a and 11_b, forward (see Fig. 5), or backward (see Fig. 4). Since a row formed in one manner is the reverse of the other, if the direction is alternated with each row (see Fig. 6), it makes no difference upon the finished article which way the weave has been started. For if the article is turned over in one's hand it appears to begin in a direction opposite to that actually woven.

Assume for the purposes of illustration that the weave has been begun by working from right to left and by bending 11_a and 11_b of the upper curved portion 12_a forward (see Fig. 5 and 5 in Fig. 6). The upper curved portion 12_a is bent forward in such a manner as to form with an immediately contiguous and adjacent lower loop (in this case the succeeding lower loop 13_b) a two-layer loop or eyelet 18 (see Fig. 5). This two-layer loop 18 serves as an eyelet for threading through the upper loop 12_a of the next succeeding row of stitches so that there will be a hinge connection between adjacent two-layer loops of each succeeding row of stitches. Any number of single-layer loops 12_a etc. are bent over to form a desired width of belt or woven material.

To form the next or succeeding row 4, after the desired width of the preceding row 5 has been attained, the curved portion 13_a is straightened (see Fig. 6) and the next single-layer loop 12_b is threaded through an adjacent or immediately preceding two-layer loop 100

18 of the upper row 5 and bent over, to itself form a two-layer loop 18', as before explained (see Fig. 6). This succeeding row (designated as 4 in Fig. 6 and shown in Fig. 4) comprises a plurality of double-layer loops substantially the same as those of the preceding row, only threaded through and bent over in reversed direction. These loops 4 are formed by bending the single-layer loops backward at 11_a and 11_b, across the lower curved portion of the preceding loop 13_a, to form a two-layer loop or eyelet 18'.

In order that there will be hinge connection between the adjacent loops of each succeeding rows of loops, as before explained, each upper loop 12 of each alternate or succeeding row is threaded through the adjacent two-layer loops of a preceding row in a direction opposite to the threading of that row through its preceding row of two-layer loops. It must be understood that these loops can be threaded through in like direction to a preceding row, if such a style of weave is desired, but the inventor in the preferred embodiment shown, has alternated the direction of the hinge-connected two-layer loops to form a more attractive weave. The hinge-connection between the rows of the article is accomplished by threading the upper curved or looped portions of the single-layer loops 12, etc., through the double-layer loops or openings 18 or 18' of the preceding row, and in bending those single-layer loops at 11_a and 11_b to form the next row of two-layer loops.

Belts made in accordance with the above are particularly adapted for sport wear, and in order to add to the appearance of such articles and render such articles adaptable to a wide range of sport costumes, I crochet into the strands formed by the stitches 11, yarn of any desired color or material, as shown at 16 in Fig. 1. It will be obvious to those skilled in the art that such yarn may be quickly and cheaply removed from the article and new yarn of different color or quality may be substituted. The wire portion of the belt will last indefinitely and may be cheaply manufactured.

An important advantage of the present weave is that it provides a hinge effect between each row of stitches. This renders the article very pliable and flexible.

While I have illustrated a belt as one embodiment of the invention, it will be apparent to those skilled in the art that the present weave may be employed for forming hollow articles or articles of any shape such as bags, hammocks, dolls, etc. Such articles may be cheaply made and present a very attractive appearance. The present weave may also be employed for a wide range of purposes without departing from the spirit and scope of the appended claims.

What I claim as new and desire to secure by Letters Patent is:

1. A wire article formed of a continuous length of wire with rows of double-loop stitches, the upper loops of each row of stitches being threaded through and bent over the loops of the adjacent row of stitches.

2. A wire belt formed of a continuous length of wire with rows of double-loop stitches extending across and forming the width of the belt, each intermediate row having its successive stitches engaging those of the adjacent rows forming a hinge connection between each row, substantially as described.

3. The combination with a wire article in accordance with claim 4, of a plurality of yarn stitches crocheted into the said article.

4. A wire article formed of a continuous length of wire with rows of double-loop stitches, an upper loop of a row of stitches being bent over so as to form a two-layer loop with a contiguous lower loop.

5. A wire article formed of a continuous length of wire with rows of double-loop stitches, each upper loop of each row being bent over a contiguous loop of the lower row so as to form with each of those loops eyelets for each upper loop of a subsequent row.

6. A wire article formed of a continuous length of wire with rows of double-loop stitches, each upper loop of each row being threaded through and bent over each two-layer loop of the preceding row of stitches, each of said two-layer loops consisting of the combination formed by bending each upper loop of the preceding row of stitches over a contiguous lower loop.

7. A wire article formed of a continuous length of wire with rows of double-loop stitches, upper loops of a row of said stitches being bent over so as to form a two-layer loop with an immediately succeeding lower loop.

8. A wire article formed of a continuous length of wire with rows of double-loop stitches, upper loops of a row of said stitches being bent over so as to form a two-layer loop with an immediately preceding lower loop.

9. A wire article formed of a continuous length of wire with rows of double-loop stitches, each upper loop of each row being bent over an immediately adjacent lower loop, so as to form an eyelet for each upper loop of a subsequent row.

10. A wire article formed of a continuous length of looped wire, the upper loops of said wire being bent across one of their sides to form two-layer loops with said sides and adjacent lower loops, each subsequent row of said article being formed by successively threading its upper loops through adjacent two-layer loops of a preceding row, and subsequently, by bending said upper loops across one of their sides to form two-layer loops with adjacent lower loops.

11. A wire article formed of a continuous length of single looped wire, the first row of said article being formed by bending each upper loop over and across one of its sides to form a two-layer loop, the next succeeding row being formed by threading each upper loop of said row through an adjacent two-layer loop of the preceding row, the said upper loop after threading through being bent over and across one of its sides to form a two-layer loop, the upper loops of each alternate row being threaded through and bent over opposite in direction to the other rows, so as to alternate the weave of said article.

15. 12. The method of forming a wire article which includes the steps of looping a continuous length of wire, and of bending the upper loops of said wire over and across one of their sides to form a two-layer loop with a contiguous lower loop.

13. The method of forming a wire article which includes the steps of looping a continuous length of wire, and lapping the upper loops of said wire over their sides to form double loops with the lower loops of said wire.

14. The method of forming a wire article having rows of stitches, which includes looping a continuous length of wire, lapping the upper loops of the wire over one of their sides for forming a double-loop row with the lower loops of said wire, and after the desired length of row is completed, in threading through upper loops of the wire through the double loops of the preceding row, and in bending the upper loops over one of their sides for forming a succeeding row of double loops.

15. A wire article formed of a continuous length of looped wire, each row of loops having a double form and being connected with adjacent rows by single portions of the double loops thereof.

16. A wire article formed of a continuous length of looped wire, the upper loop of a row of said article being bent to lap the lower loop of said row, so that a double-loop row will be formed.

17. A wire article formed of a continuous length of looped wire with rows of stitches, the upper loops of a row of stitches being bent to lap the lower loops of said row so that a double-loop row will be formed, the upper loops of a succeeding row of stitches being threaded through the double loop of the preceding row and being bent to lap the lower loops of their own row of stitches to form a succeeding double-loop row of stitches.

18. A wire article formed of a continuous length of looped wire with rows of stitches, each upper loop of each row being bent over an adjacent lower loop, so as to form a double-loop eyelet for each upper loop of a subsequent row, loops of the last row of stitches

being bound together by a common wire to form an end for the article.

In testimony whereof, I have hereunto subscribed my name this 25th day of February, 1928.

PETER J. SHRUM.
